UNITED STATES PATENT OFFICE.

EDWARD BERNARD HESS AND LEWIS CARY MYERS, OF BROOKLYN, NEW YORK,
ASSIGNORS TO ROYAL TYPEWRITER COMPANY, INC., OF NEW YORK, N. Y.

SCALE FOR TYPEWRITING MACHINES.

1,417,911.

Specification of Letters Patent. Patented May 30, 1922.

Original application filed January 13, 1921, Serial No. 436,924. Divided and this application filed May 27, 1921. Serial No. 473,173.

To all whom it may concern:

Be it known that we, EDWARD BERNARD HESS and LEWIS CARY MYERS, both citizens of the United States, residing in Brooklyn, 5 county of Kings, city and State of New York, have invented certain new and useful Improvements in Scales for Typewriting Machines, of which the following is a specification.

10 This application is a division of our application for patent filed Jan. 13, 1921, No. 436,924.

This invention relates to devices for holding cards, envelopes, etc., in printing position on the platen, and which are provided with indicating scales.

According to this invention means is provided for securely holding the card, envelope or the like in place and for readily 20 attaching it to a suitable part of the machine.

In the accompanying drawings:—

Figure 1 is a front elevation of a portion of a typewriting machine with our improvements applied.

25 Figure 2 shows a section on the line 2—2 of Fig. 1.

Figure 3 is a front elevation of the scale detached.

30 The carriage platen is indicated at A, the type-bar segment at B, and the type guide at C. A ribbon guide or vibrator is shown at D, and a part of the carriage frame at E. The shift rail F is supported by a frame G 35 to which the vibrator is connected, as indicated at g. H indicates a card scale.

The scale, shown detached in Fig. 3, comprises an upper, horizontal, graduated plate h, formed with outwardly turned curved 40 ends h', and it has a central opening h². It is also formed at its outer end with projections h³ which are adapted to bear against the card, envelope or paper being printed. Similar projections i are formed on the plate

45 on opposite sides of, and near, the central opening h², and there are also projections j interposed between the projections h³ and i. The scale is graduated, as shown, the scale marks extending along the upper edge of 50 the plate and also into the projections.

In this way the card or envelope printed upon is very securely held in place, and the scale is especially useful when the bottom portion of the envelope is being printed.

These devices also cooperate very nicely 55 with the paper rolls K located above them and which are adjustable towards and from each other on the rod K'.

The scale plate h is attached by means of screws l to the upper parts of the side members of the bracket which are connected by a cross-piece L'. The upper portions of these side members are extended downwardly, rearwardly and then downwardly again, as indicated in Fig. 2, and are attached as at g, to the front portion of the frame G below the shift rail. The side members L are prolonged to a considerable extent above the upper edge of the scale plate, providing fingers l³ which bear firmly 70 on the card or article being held.

The cross-piece L' is provided with a pointer l² cooperating with a carriage scale S of the usual kind.

The scale H contains novel features and 75 the construction is such as to enable the scale to be properly associated with the type guide C and the ribbon vibrator D.

The members L, connected by the cross-piece L', constitute a bracket for supporting the scale plate and for connecting it to the subframe of the carriage.

We claim as our invention:

1. A scale for typewriting machines having a central opening and carrying on each 85 side of the opening a plurality of projections adapted to bear on the card, envelope or paper with which it engages, and a bracket to which the scale is secured and which is rigidly attached to the shift frame. 90

2. A scale for typewriting machines having a central opening and at its upper edge a plurality of projections extending across the line of print, and a bracket to which the scale is secured, having portions attached 95 to a vertically movable part of the machine and having a central portion provided with a pointer.

3. A scale for typewriting machines having projections on its upper edge adapted 100 to bear against the card, envelope or paper with which it engages, a bracket to which the scale is secured provided with a pointer and having fingers projecting above the scale.

4. A scale for typewriting machines provided with a central opening and having a plurality of projections at its upper edge

- on each side of the central opening, and a bracket to which the scale is secured comprising two members having projections above the scale and parts below the scale
- 5 adapted to be secured to a part of the carriage frame and provided with a pointer arranged centrally of the machine.
5. A scale for typewriting machines having a central opening and at its upper edge
- 10 a plurality of projections extending across the line of print, a bracket to which the scale is secured having portions attached to a part of the machine and having a central portion provided with a pointer, all of these parts being movable upwardly when the 15 platen is shifted.
6. A scale for typewriting machines having a central opening and carrying on each side of the central opening a plurality of projections adapted to bear on the card, envelope or paper which it engages, and means for supporting the scale on a part of the machine which is raised and lowered with the platen but not otherwise.
- In testimony whereof, we have hereunto 25 subscribed our names.
- EDWARD BERNARD HESS.
LEWIS CARY MYERS.
